UNITED STATES PATENT OFFICE.

JAMES ELMER HOOKER, OF TAMPA, FLORIDA.

ROOF COVERING.

Application filed August 26, 1925. Serial No. 52,601.

To all whom it may concern:

Be it known that I, JAMES ELMER HOOKER, a citizen of the United States, and resident of Tampa, in the county of Hillsborough and State of Florida, have invented certain new and useful Improvements in Roof Coverings, of which the following is a specification.

My invention is an improvement in roof 10 coverings of the class which comprises a plurality of shingles of the lock-down type, and it consists in the combinations, constructions, and arrangements herein described and claimed.

15 An object of the invention is the provision of a roof covering of the character described which comprises a plurality of novel roofing units arranged in courses with the respective units of adjacent courses disposed 20 in staggered relation with adjacent shingles of adjacent courses lapped and locked both to each other and to the roof sheeting so that the exposed portions of the shingles will be held flatwise in the roof construction and 25 will be held securely against curling upward, warping or becoming loosened as a result of exposure to the weather and to winds or like stresses.

A further object of the invention is the provision of a novel roofing unit which comprises a novel shingle which can be applied in proper position in forming a roof without there being any necessity of first marking off lines on the roof sheeting in order to 30 assure the proper positioning of the respective shingles, the unit also including a locking strip and fastening means associated therewith and adapted to cooperate with the shingle to secure an exposed flap 35 portion of the shingle and a portion of an underlying shingle to the sheeting without the fastening means being exposed to the weather.

40 A further object of the invention is the provision of an economical roof covering comprising roofing units easy to apply and each including a shingle adapted when applied to have a relatively large portion thereof covered or lapped by adjacent shingles with but relatively little weight per 45 square of roof covering, whereby a given area of roof sheeting can be covered by a relatively few shingles of but relatively little weight per square of roof covering.

50 A still further object of the invention is the provision in a roofing unit of a shingle

which can be produced in large quantities in but relatively little time and at but relatively little cost.

Other objects and advantages of the invention will be apparent from the following description, considered in conjunction with the accompanying drawings, in which

Figure 1 is a plan view of an eaves portion of a roof construction embodying the invention.

Figure 2 is a section substantially along the line 2—2 of Fig. 1.

Figure 3 is a section through the portion of the roof covering shown in Fig. 1 with the roof sheeting omitted, the view being taken substantially along the line 3—3 of Fig. 1,

Figure 4 is a perspective view of an improved shingle which is comprised in a roofing unit embodying the invention, and

Figure 5 is a perspective view of a locking strip which also is comprised in the roofing unit with the ends of the clamping portions of the strip shown in full lines in their downwardly bent or clamping positions and in dash lines in their upstanding positions.

The improved shingle is formed of a suitable composition material which may be felt saturated with suitable waterproofing and heat resisting material. The improved shingle comprises a substantially rectangular body 1 having a pair of spaced flaps extending laterally of the body 1 along one longitudinal edge of the latter. The flaps 2 may be formed by providing a middle cut out 3 and a pair of corner cut outs 4 in one longitudinal edge portion of a rectangular sheet of material (not shown) from which the shingle may be formed, the middle cut-out being midway of the respective corner cut outs 4 and being twice as wide as each of the latter. The adjacent walls of each cut out 49 pin each other at a right angle, whereby the side edges of each flap 2 will be parallel and 55 will extend at right angles to the direction of length of the body of the shingle.

A substantially U-shaped locking strip is provided for each flap 2 and comprises an attaching web portion 5 and a pair of upstanding clamping arms or end portions 6.

The shingle and the locking strips for the flaps of the shingle comprises a roofing unit. A plurality of the roof units are used substantially as follows in forming a roof 100 covering.

A starter strip 7 having a width greater

than the length of the flaps 2 but less than the width of one of the improved shingles is secured on the roof sheeting 8 along the eaves of the roof. The starting strip preferably is formed of the same material as the body of each of the improved shingles.

A lower course of the improved shingles then is placed on the roof sheeting in position to overlap the starting strip and with 10 the flaps 2 at the lower sides of the bodies of the lower course of shingles and substantially flush at their ends with the lower edge of the starting strip 7. The web or attaching portion 5 of the locking strip for each 15 flap 2 of the shingles of the lower course is secured on the underlying starting strip and to the roof sheeting by a nail 9 which is projected through an opening 10 in the attaching portion 5 through the starting 20 strip into the sheeting so that the attaching portion 5 of the locking strip extends transversely of the associated flap 2 beneath the end portion of the flap. The end portions 25 of the locking strip then are upstanding at the side edges of the associated flap 2 but are bent inwardly and downwardly onto the flap 2 to secure the latter against upward displacement from the roof sheeting. The locking strips are made of a suitable 30 bendable material which will not corrode easily, such as zinc, copper or like metal.

Each shingle is formed with slits 11 extending transversely of the shingle into the body 1 at the corners of the cut-outs 3 and 35 4 and therefore at the inner ends of the side walls or edges of the flaps 2. The shingles of the second course are arranged in overlapping relation to the shingles of the first or lower course so that the clamping ends 40 6 of the locking strips for the flaps 2 of the second course will extend upwardly through the slits 11 at the corners of the cut-outs 3 and at the corners of adjacent cut-outs 4 of the underlying shingles, the nails 9 which 45 secure the attaching portions 5 of the locking strips for the flaps of the shingles of the second course in place also extending through the bodies of the shingles of the lower course. The extremities of the clamping 50 portions of the locking strips for the flaps 2 of the second course are bent inwardly and downwardly onto the associated flaps which thus will be locked to the bodies of the underlying shingles, as well as to the roof sheeting. The respective shingles of the 55 two adjacent courses referred to will be secured in place in the manner described with the flaps or exposed portions thereof disposed in staggered relation. The remaining 60 course of shingles will be laid in the same manner as the second course, the flap portions of the shingles of adjacent courses being disposed in staggered relation and the shingles of each course overlapping the 65 bodies of the shingles of the course next

therebelow. The nails 9 will be completely covered by body portions of the shingles and only the extremities of the clamping ends 6 of the locking strips will be exposed to the weather.

It will be manifest that I may make use of more than one nail 9 for each locking strip if I so desire without departing from the spirit and scope of the invention. Also, the locking strips may be of any desirable width.

Many modifications and adaptations of the form of the device which is illustrated in the drawings may be provided and I therefore consider as my own all such modifications and adaptations thereof as fairly fall within the scope of the appended claims.

I claim:

1. A shingle of the lock down type having a body formed with an extending flap portion and with slits in the body at the inner ends of the sides of said flap portion, and a fastening device adapted to be secured to an underlying shingle and having portions extending through said slits for clamping the flap portion of an overlapping shingle onto said first named shingle.

2. A shingle of the lock down type having a body formed with an extending flap portion and with slits in the body at the inner ends of the sides of said flap portion, and a substantially U-shaped locking strip having a flat web portion adapted to be secured in place under the body of said shingle on a portion of an underlying shingle and having upstanding end portions adapted to extend through said slits in straddling relation to the flap portion of an overlapping shingle and to be bent inward and downward onto the flap of the last named shingle to secure the latter in place on the body of the first named shingle.

3. A shingle having a body formed with a plurality of parallel extending flap portions and with slits in the body at the inner ends of the sides of said flap portions, and a substantially U-shaped locking strip for each flap portion, said locking strip having a web portion adapted to span the distance between adjacent slits in the shingle or in adjacent shingles of the same course and having upstanding end portions extending through said adjacent slits and being bendable to secure a flap portion of a shingle of the course next thereabove in place on said shingle or adjacent shingles of the first named course.

4. A shingle having a body formed with a plurality of parallel extending flap portions and with slits in the body at the inner ends of the sides of said flap portions, and a substantially U-shaped locking strip for each flap portion, said locking strip having a web portion adapted to span the distance between adjacent slits in the shingle or in adjacent shingles of the same course and having upstanding end portions extending

through said adjacent slits and being bendable to secure a flap portion of a shingle of the course next thereabove in place on said shingle or adjacent shingles of the first 5 named course, the attaching portion of each locking strip being adapted to be secured by a nail to a fixed support, the nail being completely covered by an overlapping shingle.

5. A roofing unit comprising a shingle having an extending flap portion and a locking strip attachable to a support underneath said flap portion and having end portions adapted to be bent across the edges of the flap portion and onto the flap portion to hold it in place.

JAMES ELMER HOOKER.
